No 220 St. G. Banova

Design for ottoman

Patented 24th April 1874. —

Fig. 1.

Fig. 2.

Nos. 220

S. H. Ransom; Albany N.Y. Letters Patent No 220. dated
April 24th 1849.

The Schedule referred to in these Letters Patent & making part of the same.

To all whom it may concern:

Be it known that S. Samuel H. Ransom, of Albany in the County of Albany and State of New York, have invented or produced a new ornamental design for a cooking stove, and I do hereby declare that the accompanying drawings are full and accurate delineations of a stove after my said design; Fig 1. being a front & Fig 2 a side view. a is a portion of the moulding around the edge of the top plate.

Ms. 220

23

What I claim as my invention and desire to secure by Letters Patent is the combination and arrangement of ornamental forms and figures represented in the accompanying drawings forming an ornamental design for a cooking Stove.
